UNITED STATES PATENT OFFICE.

CHARLES J. PILLING, OF PHILADELPHIA, PENNSYLVANIA.

APPARATUS FOR MEASURING AND INDICATING BLOOD-PRESSURE.

1,153,251.

Specification of Letters Patent. Patented Sept. 14, 1915.

Application filed February 5, 1912. Serial No. 675,590.

To all whom it may concern:

Be it known that I, CHARLES J. PILLING, citizen of the United States, residing in the city of Philadelphia, State of Pennsylvania, have invented certain new and useful Improvements in Apparatus for Measuring and Indicating Blood-Pressure, of which the following is a full, clear, and exact description, reference being had to the accompanying drawings, forming a part of this specification.

My invention relates to apparatus adapted especially for use in pathological diagnosis, for measuring, and indicating on a pressure-scale, the pressure of the blood in any artery of the human body adapted to be constricted by suitable means such as any usual form of expansible tourniquet; and it especially relates to the particular type of such apparatus described in U. S. patent to Francis Ashley Faught, No. 917,276 dated April 6, 1909, wherein the apparatus, of that type, exemplifies the principle involving a closed pneumatic system comprising a mercury manometer, a constriction device adapted to be applied to and to make a circular pressure upon an artery-containing portion of the human body, such as the fore-arm, a source of compressed air-supply, and connecting tubular means to supply an increasing air-pressure between the constriction device and one end of the mercury column on the manometer, with a pressure-scale adapted to note such increasing pressure and the degree to which it shall fall when constriction of the artery is released and the arterial pulse-beat noted, by means of a suitable valve adapted to release the air-pressure in said tubular connections.

My improvements are predicated on the particular example of such apparatus described in said Faught patent, and consist of a novel character of manometer tube, a novel form of rigid tubular connection between it and the flexible tubes leading respectively to the source of compressed air-supply and the constriction device, and a new relative arrangement of the several elements, except the rectangular containing casing of that apparatus, with its pivoted lid on which the manometer tube with its rigid tubular connections is mounted. This form of containing case and its mounting lid I have adopted without change and hence they form no part of my present invention herein described

and claimed, save in the specific features of improvement thereof as hereinafter stated.

In the accompanying drawings illustrating my invention: Figure 1 is a front or end elevation, partly in section, with the pivoted lid of the casing in raised position, hence showing the manometer in vertical and operative position, and showing also the flexible tubular connections leading respectively to the constriction device (not shown) and to the source of compressed air supply which is shown in full in elevation. Fig. 2 is a like view, in side elevation, except the aforesaid flexible tubular connections and air-pump, which are removed. Fig. 3 is a sectional detail showing the link and its coöperating pin for holding the pivoted lid in the raised position.

Referring now to said drawings, the rectangular containing casing A, its pivoted lid A', operating as a closure for the casing and as a mounting for the manometer tube, with the hinge pins, a, a, link connection h, and brackets b, b' to support the manometer tube and its adjunctive parts, are precisely the same as shown and described in said Faught patent, to which reference is made for further description if need be, though they are clearly shown in the drawings hereto annexed. To such a containing casing I add a spring guide-clip d which clamps the edges of a pressure-scale board C and permits of a sliding-adjustment of said pressure-scale board C, which latter is also the same as in said patent referred to; and I mount in the basal interior of the casing a pair of spring clips s, s, between which the air-pump S may be conveniently held detachably, when not in use.

One end of the link h is pivoted, at h³, to a bracket h² secured to the lid A. The link h has a longitudinal slot h¹ therein, and extending through the slot h¹ is a pin h⁴ which is fixed to the side of the casing A. The upper wall h⁶ of the slot h¹ is pressed against the pin h⁴ which extends around the pin h⁴ and has its upper end bearing against the lower wall of the slot h¹ and its lower end secured to the adjacent side of the casing A. The upper wall h⁶ of the slot h¹ has an off-set h⁷ therein, forming a socket, as clearly shown in Fig. 3, which is moved down around the upper portion of the pin h⁴ by the pressure of the spring h⁵ when the lid A' is in the upright position shown in the

drawings, thereby causing the link h to hold the lid A' firmly in the operative or upright position. When it is desired to lower the lid A' to close the casing A , the link h is 5 lifted manually to free the socket h^7 from the pin h^4 , and the lid A' is lowered; and, during the lowering of the lid A' the upper and lower walls of the slot h^1 slide against the pin h^4 and the spring h^5 . It will therefore be understood that when the lid A' is 10 raised the walls of the slot h^1 will slide against the pin h^4 and spring h^5 and also that when the lid reaches the upright or operative position the spring h^5 will automatically engage the socket h^7 with the pin h^4 to retain the lid in such upright position.

Mounted on the inner face of the hinged casing lid A' is a mercury manometer B consisting of a glass tube having a long vertically disposed portion, open at the top, and supplied thereat with an air-nipple c governed by a stop-cock c' . At its basal end the manometer tube is bent upward on a large curve and terminates in a vertically-disposed and relatively-large chambered end B' , which is operatively closed; though it is constructed with an open upper end through which passes a depending tapered glass air-tube m^3 for a purpose to be presently explained.

For convenience of construction the glass mercury chamber or bulb B' is molded or blown with an integral extension end indicated in dotted lines at m^2 , which carries 35 within it the tapered glass tube m^3 which dependingly projects downward within the bulb B' to about half the depth thereof. The said extension end m^2 of the bulb and the lower end of the rigid tube m , about to 40 be described, are operatively connected by a rubber tubular covering m' .

In U-spaced manometer tubes and the like, employed in apparatus of this class, a serious inconvenience and loss, amounting to a 45 defect in operation, is experienced in the mercury discharging, to some considerable extent, into the tubular connections adjacent thereto, on a release of the air-pressure after constriction is effected; and this is entirely obviated in my device by providing the mercury tube with a relatively large bulbous end and leading the compressed air to and from the same through the medium of the small air-tube m^3 which extends dependingly into the mercury bulb B' and above the zero-line of contained mercury.

The manometer tube is held in place at top and bottom on its hinged mounting-board A' , by brackets b and b' . A small 60 spring-clip mounted in a guiding bracket d secured to said board A' supports a pressure-scale board C by frictional contact therewith, whereby it is held in vertically adjustable register with the manometer tube. Rigid tubular connections, preferably of

metal, consist of a tube m , mounted on the hinged board A' by brackets d' , d^2 , said brackets being each made preferably with an integral tubular hub d^3 , d^4 , each terminating in a nipple d^5 , d^6 , and for economy and convenience of construction the tube m communicates with the interior of the hubs d^3 and d^4 , and also passes through the hub d^4 , and at its lower end operatively communicates with the mercury bulb B' of the manometer tube, through the medium of the small glass air-tube m^3 which projects into the interior of said bulb.

Mounted detachably on the nipple d^5 is a flexible tube g leading to any suitable form of arterial constriction device, such as that shown in Faught's patent before referred to. Mounted detachably on the lower nipple d^6 is another flexible tube which leads to and is connected with the discharge end d^7 of an air-pump, whereby the required volume of compressed air is supplied to the instrument. This air-pump is constructed with a barrel S , with the usual piston carried by a hollow piston rod s actuated by a pair of finger-grasp handles s' , s'' , the upper end of the piston-rod opening into a hubbed discharge end d^7 provided with a sensitive release valve indicated at t . For a fuller description of this element of the device, which contains several novel features, reference is made to Letters Patent to me, No. 1,054,866, dated March 4, 1913, in which it is more fully shown and described.

Concerning the operation of the device, it 100 need only be said, in addition to the description given, that the manometer being charged with mercury until it reaches a level in the bulb B' on a line with zero mark on the pressure scale, the opening c , at top, is closed; the hinged lid A' being previously raised out of the casing to operative vertical position, as shown, and held in that position by the spring h^5 forcing the recessed portion h^4 of the slot in the link into register with the pin H . The pump barrel, with its attached flexible tube f , detached from its holding clips on the body of the casing, and said tube, as also flexible tube g leading to the constriction device, being attached to 105 nipples d^5 and d^6 in the order shown and described, air-pressure created by operation of the pump piston extends equally to the manometer as to the constriction device, until at the appropriate time the sensitive release valve t is operated to release the air compression; and the position of the mercury column relatively to the scale markings noted at the first pulse beat felt, which will indicate the exact pressure in the artery.

Having thus described my invention, I claim as new and desire to secure by Letters Patent:

1. In an apparatus of the class recited, the combination of a containing casing, a lid 130

pivoted near one of its ends to said casing, a manometer tube fixedly mounted on said pivoted lid, said lid and the tube thereon being adapted to be moved to a perpendicular 5 and operative position, a pin secured to said casing, a link pivoted to said lid and having a part adapted to engage said pin and support said lid in said perpendicular position, and a spring adapted to automatically 10 move said link into engaging position with said pin to support said lid when it is moved to said perpendicular position.

2. In apparatus of the class recited, the combination of a containing casing, a lid pivoted near one of its ends to said casing, a manometer tube fixedly mounted on said pivoted lid, said lid and the tube thereon being adapted to be moved to a perpendicu-

lar and operative position, a pin secured to said casing, a link pivoted to said lid and having a longitudinal slot therein through which said pin extends, one wall of said slot having an off-set adapted to engage said pin and support said lid in said perpendicular position, and a spring adapted to automatically move said link so as to force said off-set into engagement with said pin to support said lid when it is moved to said perpendicular position. 20 25

In testimony whereof, I have hereunto affixed my signature this thirtieth day of January A. D. 1912. 30

CHARLES J. PILLING.
